UNITED STATES PATENT OFFICE.

THOMAS LINCOLN AND DANIEL S. WESSON, OF NEW HAVEN, CONNECTICUT.

DESIGN FOR A CLOCK-CASE.

SPECIFICATION forming part of Design No. 12,759, dated February 7, 1882.

Application filed January 9, 1882. Term of patent 3½ years.

To all whom it may concern:

Be it known that we, THOMAS LINCOLN and DANIEL S. WESSON, of New Haven, in the county of New Haven and State of Connecticut, 5 have invented a new Design for Clock-Cases; and we do hereby declare the following, when taken in connection with accompanying drawing and the letters of reference marked thereon, to be a full, clear, and exact description of 10 the same, and which said drawing constitutes part of this specification, and represents a front view.

This invention relates to a design for clock-case, with special reference to the small clock 15 known in the market as the "Yale Gem," but applicable to other styles or classes of clocks; and the invention consists in the configuration and ornamentation of the front, as shown in the accompanying illustration.

20 The base represents scroll-work springing from each side inward toward the center, downward, and upward, leaving a space at the center bordered by a branch of flowers springing from the scroll-work on the front. Between 25 the scroll-work is the representation of a dog.

From the scroll-work the case extends up each side, terminating in semicircular shape at the top. In the center is the opening for the dial, the surface around it above the base ornamented by floriated tracery, as shown in the accompanying illustration. 30

The ornamentation in the center below the dial-opening, which here represents a dog, may be changed and other ornamentation there introduced, or it may be left plain. 35

We claim—

The herein-described design for clocks, consisting of the scroll-work base springing from each side inward, leaving a space in the center bordered by a branch of flowers, and above 40 the base, extending upward, terminating in a semicircular shape, with the dial opening on the front, the surrounding surface ornamented by floriated tracery, as shown in the accompanying illustration. 40

THOMAS LINCOLN.
DANIEL S. WESSON.
